UNITED STATES PATENT OFFICE.

BENJAMIN WEXLER, OF BROOKLYN, NEW YORK, ASSIGNOR TO THE PEELLE COMPANY, A CORPORATION OF NEW YORK.

LOCKING MECHANISM FOR AUTOMATIC ELEVATOR-DOORS.

1,381,263.

Specification of Letters Patent. Patented June 14, 1921.

Application filed November 2, 1918. Serial No. 260,838.

To all whom it may concern:

Be it known that I, BENJAMIN WEXLER, a citizen of the United States, residing at the borough of Brooklyn, in the city of New York, county of Kings, and State of New York, have invented certain new and useful Improvements in Locking Mechanisms for Automatic Elevator-Doors, of which the following is a specification, reference being had 10 therein to the accompanying drawings, which form a part thereof.

My invention relates to locking mechanisms for automatic elevator doors, and more particularly to a mechanism for use in 15 combination with counterweighted self-opening doors, provided with suitable means whereby any open door may be automatically closed.

In elevator doors of the type to which my 20 invention relates, each door opening in a shaft is closed by a single paneled, vertically sliding door, there being provided a single source of power controllable from within a car, and actuating means connected thereto 25 with and common to all doors in a shaft, whereby any door, when open, may be closed from this single source of power. Each door is provided with its own counterweight, so that when the door is released 30 through this source of power, it will automatically open to the full extent. While the actuation means connected with this source of power will normally lock all of the doors in a shaft, the actuation of this 35 means, by the source of power, to permit the opening of one door, will have the same operative effect as to all doors in a shaft, thus necessitating the employment of supplemental locking means for each door in 40 a shaft.

With this condition in mind, the object 45 of my present invention is to so construct an elevator door of this type, that no door in the shaft can be opened unless an elevator car is at the door opening closed thereby, and that when an elevator car is stopped at any door opening, the door at that opening may be opened by the controlling means for said source of power, without requiring any further attention from the operator. The supplemental locking means through which this 50 effect is secured, is so constructed that with the passage of a car up and down a shaft, it may be released as to each door and will be

automatically restored to its locking position 55 in the event that a car does not stop at that floor. In this manner the supplemental locking means will always be operative as to all doors in a shaft, excepting the door at an opening where the car may be positioned. 60

The invention consists in a locking mechanism for automatic elevator doors embodying therein the novel features of construction and combination of parts hereinafter set forth and described, and more particularly pointed out in the claims hereto appended.

Referring to the drawings,

Figure 1 is a front elevation showing the elevator door equipment on a plurality of 70 floors of a building, said equipment embodying my invention;

Fig. 2 is a front view of one of the locking mechanisms applied to an elevator door; 75

Fig. 3 is a side view of the mechanism shown in Fig. 2, together with a fragmentary portion of an elevator car.

Like letters refer to like parts throughout 80 the several views.

In the embodiment of the invention shown in the drawings, *a* and *b* indicate single paneled, vertically sliding doors, closing openings at different floors in an elevator shaft. Counterweights *a'* are operatively connected 85 with the door *a* upon opposite sides thereof, by means of flexible chains, cables or strips *a''*, passing over sheaves *a'''*. Similar counterweights *b'* are connected with the door *b*, through chains, cables or strips *b''*, passing 90 over suitable sheaves *b'''*. The aggregate load of the weights *a'* and of the weights *b'*, is sufficient to overbalance the doors *a* and *b* respectively, and thus have a normal tendency to raise said doors. 95

Each door in a shaft is provided, on opposite sides thereof, with laterally extending flanged projections, through which power is applied to close any door. These projections upon the door *a* are indicated at *c*—*c'*, and 100 those upon the door *b*, at *d*—*d'*. Extending upon opposite sides of all door openings in the shaft, are flexible chains, cables or strips *e*—*f*, passing through an opening in the projections *c*—*d* and *c'*—*d'* respectively, and 105 having mounted thereon, adjacent each door opening, a stop ball or block *e'*—*f'*, adapted to operatively engage the extension of the

door closing said opening, through which the chains, cables or strips $e-f$ pass, to permit said cables to be used as actuating means for overcoming the weight a' or b' when it is desired to close the door.

The chains, cables or strips $e-f$ pass over pulleys e^2-f^2 at the top of the shaft, and have connected therewith weights e^3-f^3 sufficient to overcome the load of these cables 10 and the parts appurtenant thereto. Said cables also pass over sheaves e^4-f^4 at the bottom of the shaft, and about a sheave g , the ends of said cables being connected to a single cable h connected with any desired 15 source of power, as the piston rod of a pneumatic motor i . The power for said motor is controlled electrically from an elevator car by means of an ordinary electrically actuated valve j , a single pipe j' serving to lead the 20 air to one end of the cylinder of said motor, and to permit the venting of said cylinder. A switch mechanism k carried by the elevator car m , controls the circuit k' to the valve mechanism j .

25 Mounted upon the supporting structure for the guides or tracks upon which each door in a shaft slides, and adjacent the sill of the door opening, is a pivotal latch lever n , the hooked head n' of which is normally projected in the path of movement of the projection c, c', d or d' , and the heel n^2 of which is adapted to abut against the wall adjacent said lever, as clearly shown in Fig. 3. Intermediate the point of pivotal support of said lever and its head, is a projecting arm o having an anti-friction roller o' , said arm being of a length to bring said roller in the path of movement of a shoe m' , carried by the elevator car m , in a manner 40 to cause said shoe to move the lever n against the tension of the spring n^3 in a manner to disengage it from its coöperating projection upon the door proper, to permit the opening of said door.

45 The operation of the herein described mechanism is as follows:—

Assuming that one door in the shaft is open, as shown in Fig. 1, the latch lever n of that door will be moved out of the path 50 of the projections $d-d'$ upon the door b , by the shoe m' upon the car m , as shown in dotted lines in Fig. 3, the weights b' holding the door in the open position and the weights e^3-f^3 holding all of the stop balls 55 or blocks $e'-f'$ upon the chains, cables or strips $e-f$ in their uppermost position. When the parts are in this position, the balls or blocks $e'-f'$ coöperating with the projections $d-d'$ will still be in engagement 60 therewith, but will be moved away from the projections $c-c'$ upon the door a and upon all other doors in a shaft. With this condition, the latch levers n upon all doors in the shaft, other than the door b , will, 65 through their operative relation with their

coöperating projections, hold these other doors closed, since were it not for the presence of this supplemental latch mechanism, all doors in a shaft would open and close simultaneously as a result of the action of 70 the weights thereon, and the movement of the actuating means connected with the motor i .

When a car is about to leave the door opening closed by the door b , the operator 75 actuates the switch k closing the circuit to the mechanism actuating the valve j , and thus admits air to the lower part of the cylinder of the motor i , raising the piston in said cylinder and exerting an upward pull 80 upon the cable h and a downward pull upon the cables e and f , thus raising the weights e^3-f^3 and causing the balls or blocks $e'-f'$ coöperating with the projections $d-d'$, to force the door downwardly to the full extent. The movement of the cables e and f will also bring the remaining balls or blocks $e'-f'$ thereon in engagement with the projections upon all of the doors in a shaft, 85 thus being in a position to block any movement of any of the doors. As the car m moves in the shaft, as it passes each door opening, the shoe m' thereon will, through its engagement with the roller o' at each door opening, oscillate the lever n in a manner to disengage it from this coöperating projection, but in the event that the elevator car does not stop at a floor, as soon as the car passes the floor, the spring n^3 90 will restore the latch lever to its normal 100 operative relation with the projection upon the door.

The heel n^2 limits the action of the spring n^3 in a manner to position this lever in the path of movement of the coöperating projection upon the door, so that when the door is open, said lever will be so positioned as to be actuated by the engagement of the projection therewith, with the closing of the door. In this manner the operative effect 110 of the latch lever is made positive, since even though a car may be started before the door is completely closed, nevertheless the supplemental latch mechanism will be fully operative.

It is preferable to duplicate the latch lever n and its appurtenances, upon opposite sides of the door.

When a car stops at the sill of a door opening, the lever n will be held out of engagement with its coöperating projection, so that to open a door it is merely necessary to actuate the switch k , thus cutting off the power to the cylinder of the motor i , and permitting the air in said cylinder to vent 120 through said valve mechanism j . As the air is vented, the weights e^3-f^3 will descend, and thus raise the chains, cables or strips $e-f$, in a manner to simultaneously move all the balls or blocks $e'-f'$ thereon and 125 130

permitting the counterweights upon the door at the opening where the car is, to descend and automatically open the door.

The construction of the motor *i* and of the valve mechanism *j*, are old and well known in the arts, and are not therefore described in detail, particularly as any other desired motive power may be used for closing the doors, without departing from the spirit and 10 scope of the invention.

It is not my intention to limit the invention to the precise details of construction shown in the accompanying drawings, it being apparent that many variations thereof 15 are within the province of the skilled mechanician.

Having described the invention, what I claim as new and desire to have protected by Letters Patent, is:—

- 20 1. A locking mechanism for automatic elevator doors embodying therein in combination with a sequence of upwardly sliding door panels, each having laterally extending projections adjacent the bottom thereof, 25 weights adapted to normally raise each of said panels, and means for automatically closing said doors, including therein strips upon opposite sides of said doors, blocks thereon adapted to engage the top of the 30 projections on each of said doors, and a motor controllable from within a car, adapted to exert a downward pull upon said strips, of supplemental locking means adjacent the sill of the door opening closed by 35 each of said panels, coöperating means forming a part of said supplemental locking means respectively, and carried by an elevator car, whereby any of said supplemental locking mechanisms is released when the car 40 is at the door opening adjacent thereto, and means whereby each of said supplemental locking mechanisms is operative at all other times.
2. A locking mechanism for automatic elevator doors embodying therein in combination with a sequence of upwardly sliding door panels, each having laterally extending projections adjacent the bottom thereof, 45 weights adapted to normally raise each of said panels, and means for automatically closing said doors, including therein strips upon opposite sides of said doors, blocks thereon adapted to engage the top of the 50 projections on each of said doors, and a motor controllable from within a car, adapted to exert a downward pull upon said strips, of a latch lever pivotally mounted 55 adjacent the sill of each door opening, and adapted to pass over and operatively engage a projection on the panel closing said opening, a spring normally forcing said lever into the operative relation to said projection, a heel upon said lever adapted to engage 60 an opposed surface and limit the operative effect of said spring, and coöperating means carried by said lever and an elevator car, respectively, whereby said lever may be actuated to release said panel when the car is at a door opening adjacent thereto.
3. A locking mechanism for automatic elevator doors embodying therein in combination with a sequence of upwardly sliding door panels, each having laterally extending projections adjacent the bottom thereof, 65 weights adapted to normally raise each of said panels, and means for automatically closing said doors, including therein strips upon opposite sides of said doors, blocks thereon adapted to engage the top of the 70 projections on each of said doors, and a motor controllable from within a car, adapted to exert a downward pull upon said strips, of a latch lever pivotally mounted 75 adjacent the sill of each door opening, and adapted to pass over and operatively engage a projection on the panel closing said opening, a spring normally forcing said lever into the operative relation to said projection, a heel upon said lever adapted to engage an opposed surface and limit the operative effect of said spring, and coöperating means carried by said lever and an elevator car, respectively, whereby said lever may be actuated to release said panel when the car is at a door opening adjacent thereto.
4. A locking mechanism for automatic elevator doors embodying therein in combination with a sequence of upwardly sliding door panels, each having laterally extending projections adjacent the bottom thereof, 80 weights adapted to normally raise each of said panels, and means for automatically closing said doors, including therein strips upon opposite sides of said doors, blocks thereon adapted to engage the top of the 85 projections on each of said doors, and a motor controllable from within a car, adapted to exert a downward pull upon said strips, of a latch lever pivotally mounted adjacent the sill of each door opening, and adapted to pass over and operatively engage a projection on the panel closing said opening, a spring normally forcing said lever into the operative relation to said projection, a heel upon said lever adapted to engage an opposed surface and limit the operative effect of said spring, and coöperating means carried by said lever and an elevator car, respectively, whereby said lever may be actuated to release said panel when the car is at a door opening adjacent thereto.
5. A locking mechanism for automatic elevator doors embodying therein in combination with a sequence of upwardly sliding door panels, each having laterally extending projections adjacent the bottom thereof, 90 weights adapted to normally raise each of said panels, and means for automatically closing said doors, including therein strips upon opposite sides of said doors, blocks thereon adapted to engage the top of the 95 projections on each of said doors, and a motor controllable from within a car, adapted to exert a downward pull upon said strips, of a latch lever pivotally mounted adjacent the sill of each door opening, and adapted to pass over and operatively engage a projection on the panel closing said opening, a spring normally forcing said lever into the operative relation to said projection, a heel upon said lever adapted to engage an opposed surface and limit the operative effect of said spring, and coöperating means carried by said lever and an elevator car, respectively, whereby said lever may be actuated to release said panel when the car is at a door opening adjacent thereto.
6. A locking mechanism for automatic elevator doors embodying therein in combination with a sequence of upwardly sliding door panels, each having laterally extending projections adjacent the bottom thereof, 100 weights adapted to normally raise each of said panels, and means for automatically closing said doors, including therein strips upon opposite sides of said doors, blocks thereon adapted to engage the top of the 105 projections on each of said doors, and a motor controllable from within a car, adapted to exert a downward pull upon said strips, of a latch lever pivotally mounted adjacent the sill of each door opening, and adapted to pass over and operatively engage a projection on the panel closing said opening, a spring normally forcing said lever into the operative relation to said projection, a heel upon said lever adapted to engage an opposed surface and limit the operative effect of said spring, and coöperating means carried by said lever and an elevator car, respectively, whereby said lever may be actuated to release said panel when the car is at a door opening adjacent thereto.
7. A locking mechanism for automatic elevator doors embodying therein in combination with a sequence of upwardly sliding door panels, each having laterally extending projections adjacent the bottom thereof, 110 weights adapted to normally raise each of said panels, and means for automatically closing said doors, including therein strips upon opposite sides of said doors, blocks thereon adapted to engage the top of the 115 projections on each of said doors, and a motor controllable from within a car, adapted to exert a downward pull upon said strips, of a latch lever pivotally mounted adjacent the sill of each door opening, and adapted to pass over and operatively engage a projection on the panel closing said opening, a spring normally forcing said lever into the operative relation to said projection, a heel upon said lever adapted to engage an opposed surface and limit the operative effect of said spring, and a shoe carried by the elevator car, and a projection upon said lever extending into the path of movement of said shoe, whereby said lever may be actuated to release said panel when the car is at a door opening adjacent thereto.
8. A locking mechanism for automatic elevator doors embodying therein in combination with a sequence of upwardly sliding door panels, each having laterally extending projections adjacent the bottom thereof, 120 weights adapted to normally raise each of said panels, and means for automatically closing said doors, including therein strips upon opposite sides of said doors, blocks thereon adapted to engage the top of the 125 projections on each of said doors, and a motor controllable from within a car, adapted to exert a downward pull upon said strips, of a latch lever pivotally mounted adjacent the sill of each door opening, and adapted to pass over and operatively engage a projection on the panel closing said opening, a spring normally forcing said lever into the operative relation to said projection, a heel upon said lever adapted to engage an opposed surface and limit the operative effect of said spring, and coöperating means carried by said lever and an elevator car, respectively, whereby said lever may be actuated to release said panel when the car is at a door opening adjacent thereto.

In witness whereof, I have hereunto affixed my signature, this 21st day of October, 1918, in the presence of two subscribing witnesses.

BENJAMIN WEXLER.
